TEMPERATURE CONTROL FOR HEAT EXCHANGE UNITS

Robert J. Stewart, Baltimore, Md., assignor to
 Crown Cork & Seal Company, Inc., Baltimore,
 Md., a corporation of New York

Application March 2, 1942, Serial No. 433,069

16 Claims. (Cl. 62—7)

The present invention relates to temperature controls for heat exchange units and, more particularly, to such a control for a refrigeration unit used in cooling an intermittently flowing stream of water.

In soft-drink bottling plants, it is necessary to cool water before it is carbonated, since carbon dioxide gas will more readily go into solution when the water is at a low temperature. For this reason, it is usual to run the water through a cooling unit before it is flowed to the carbonator or saturator. After carbonation, the water flows to a filling machine which places the carbonated water and syrup in bottles.

The practice in bottling plants is to provide for a minimum level of carbonated water in the carbonator. When the water drops to this level, a water pump is placed in operation to force water through a cooler and into the carbonator until a maximum level is reached, when the supply of water is discontinued and flow through the cooler therefore, stops, leaves water standing in the cooler. During all this operation, the filling machine is constantly draining water from the carbonator. In an average plant, the water pump will be in operation about ten minutes out of each twelve minutes, with the filler in constant operation. This system, involving intermittent supply of water to the carbonator, and hence intermittent flow of water through the cooler, insures that the carbonator will contain an excess of water beyond the requirements of the filler.

Because the water moves from the pump to the carbonator in an intermittently flowing stream, it is necessary to have the cooling capacity of the cooling unit such that it will not freeze the water standing in the unit when the pump is not in operation. This, of course, means that the cooling effect of the unit is limited. That is, since the unit must be set to insure that non-flowing water will not be frozen, its setting must also be such that a moving stream can only be cooled to a temperature substantially above freezing. Stated another way, a marked temperature differential cannot be provided between the water and the refrigerating agent because the effective temperature of the latter must always be substantially above freezing.

An important object of the present invention is to provide a control for heat exchange units whereby a greater temperature differential can be maintained between the substance being treated and the heat exchange medium.

Another object of the invention is to provide

a control for heat exchange units whereby a liquid or other substance can be cooled to an optimum extent while flowing and without danger of freezing occurring when flow stops.

5 The invention may be generally described as comprising a control whereby the effective temperature of the heat exchange unit will be at least partially controlled by the actuation of the water supply means or pump.

10 It will be apparent that greater efficiency can be obtained from a cooling unit if a marked temperature differential can be safely maintained while the water is running. For example, if a refrigerating unit of the flooded type is so controlled that the point at which evaporation occurs is raised when water flow stops and it, therefore, cannot freeze standing water, such a unit can normally be maintained under extremely low pressure and thereby cool a great volume of water to a temperature just above freezing. In addition, a refrigerating unit which includes a control to prevent it from freezing standing water can be operated to cool a moving body of water to a temperature very close to freezing.

15 Another object of the invention is to provide a control of the type described in the preceding objects, and which control is of optimum simplicity.

20 It has heretofore been proposed to control heat exchange units according to whether flow of the liquid to be cooled is occurring. However, such arrangements have been responsive to the physical presence of liquid, rather than to operation

25 of the liquid supply means and they, therefore, involved the use of flow detecting devices made unnecessary by the present invention. The refrigerant controls used by prior devices have also been far more complicated than the arrangement disclosed herein.

30 It will be understood that the description of the application of the invention to a cooling unit for water is merely for purposes of illustration and since the application of the invention to any heat exchange device and its control within critical limits will be quite apparent.

35 Other objects and advantages of the invention will be apparent from the following specification and accompanying drawing wherein:

40 Figure 1 is a diagrammatic showing of a control arrangement and circuit included in the invention;

45 Figure 2 is a diagrammatic showing of a modified control; and

Figure 3 diagrammatically shows an additional modified arrangement.

Referring to Figure 1, the numeral 10 designates an electric motor driving a water pump 11. Water to be cooled is delivered to the pump from any suitable source through the pipe 12 and flows from the pump through pipe 13 to a water coil 14 positioned in a refrigerating or heat exchange unit 15. Coil 14 extends to a water line 16 leading to a carbonator 17. When carbonated, the water settles in the lower portion of the carbonator and actuates floats 18 and 18a which, as hereinafter described, serve as controls upon the operation of the electric motor 10. As is the usual practice, during the normal operation of the bottling plant, water will be continually withdrawn from the carbonator through outlet pipe 19 to flow to the reservoir of a filling machine. However, the water pump 11 is normally only operated at intervals. For example, the water pump of a carbonator may be actuated for about ten minutes out of each twelve minutes. That is, the water level drops due to the drain upon the carbonator by the filler and the water pump then operates to raise the level and accumulate an excess supply. The motor then stops and the water level will not drop to lower the float to a critical position for another two minutes.

The heat exchange unit 15 is of the flooded type and receives liquefied refrigerant or other heat exchange medium readily vaporizable at ordinary temperatures through a pipe line 25 from a compressor 26 driven by a motor 27 through any usual controlling circuit. Pipe line 25 includes a condenser 25a. The refrigerant, in gaseous form, is withdrawn from unit 15 through return or suction line 28 by compressor 26, the quantity of suction flow being controlled by valve 29 which is adapted to cooperate with a seat 30 in the suction line. Valve 29 is adapted to be fully opened by a valve opening coil 31, and is urged toward a more nearly closed position with regard to the seat by a spring, not shown. That is, when valve opening coil 31 is energized, the valve 29 will be raised to a more widely opened position with respect to seat 30 so that lower pressure will be maintained in the unit 15 and the point of evaporation of the refrigerant lowered so that it will have a greater cooling effect. However, when the coil 31 is deenergized, the spring associated with valve 29 will move the latter to such position that the suction line 28 will be more nearly closed and a higher pressure will be maintained in unit 15, thereby reducing the cooling effect of the refrigerant.

By the construction disclosed in Figure 1, when the electrical circuit hereinafter described is set to automatically control the valve, coil 31 will normally be energized to hold valve 29 wide open so long as motor 10 is operating the water pump 11, thereby maintaining a low pressure upon the refrigerant in unit 15. When the circuit to the pump motor 10 is broken, due to the rise of water in carbonator 17, valve opening coil 31 will remain energized until the temperature of the now non-flowing water in water line 16 reaches such a low point that a thermostatically controlled switch 35 directly responsive to the temperature of the water in coil 14 is opened. When switch 35 is opened, coil 31 will be deenergized, valve 29 will move to a more nearly closed position and a higher pressure will be maintained in unit 15.

The Figure 1 circuit whereby valve opening coil 31 is controlled as stated above is as follows:

The numeral 40 designates a power line adapted to be connected by a contact 41 with a lead 42 to motor 10. The numeral 43 designates a second power line adapted to be connected by a contact 44 with a motor lead 45. Numeral 46 designates a third and common return power line arranged to be connected by a contact 47 with a motor lead 48. The contacts 41, 44 and 47 are carried by a contact supporting element 50 actuated by a switch holding coil 51. From power line 43 a wire 52 extends to one end of coil 51. A lead 55 also extends from power line 43 to one end of valve opening coil 31. A lead 58 is connected to the other end of holding coil 51, lead 58 continuing to the contact 59 of a manually operated switch diagrammatically shown at 60 and which has two closed positions. The movable contact element of switch 60 is connected by a lead 61 to the power line 46. A mercury type switch 62 controlled by the float 18 of carbonator 17 is connected by a lead 63 to lead 58 and by a lead 64 to a line 65 which extends between the other fixed contact 66 of manual switch 60 and the thermostatically controlled switch 35. The other side of thermostatic switch 35 is joined by a lead 66 to lead 58a.

The second float 18a in carbonator 17 is so mounted that a second mercury type switch 62a controlled thereby will be operated simultaneously with the switch 62 of float 18. One contact of switch 62a is connected by a lead 64a with lead 64 and its other contact is connected to lead 66 by a lead 66a.

It will be understood from the foregoing that the floats 18 and 18a cause their switches 62 and 62a to close when the water reaches a predetermined low level, the switches remaining closed until the water reaches a predetermined high level.

The operation of the electrical circuit arrangement of Figure 1 is as follows: When manual switch 60 is moved to bring its diagrammatically indicated right hand contact blade 70 against fixed contact 59, which is the manual position, i. e., the position used to test run the apparatus and which can only be maintained by an operator holding the switch closed, current will flow from power line 46 through lead 61 to the movable contact 70 and thence through lead 58 to the switch holding coil 51 and then to power line 43. The contact supporting element 50 will thereby be moved to cause the power lines 40, 43 and 46 to be connected to motor leads 42, 45 and 48 so that water pump motor 10 will be operated and pump 11 will supply water to unit 15 from which it will flow to the carbonator 17.

At the same time, the valve opening coil 31 will be energized if the floats 18 and 18a are in lowered position due to the fact that the coil is now in parallel with the above holding coil circuit through lead 55 and leads 58a, 66, 66a, switch 62a, lead 64a, switch 62, and lead 63. As a result, the water flowing through unit 15 will be cooled to maximum extent, bearing in mind its rate of flow. However, if the float switches 62 and 62a open due to the water reaching its maximum level, valve 29 will be moved to a more nearly closed position raising the pressure of the refrigerant and thereby reducing the cooling effect of unit 15. It will be observed that the above circuit is entirely independent of any control by the thermostatic switch 35.

When manual switch 60 is actuated to move its

other diagrammatically indicated contact 71 against fixed contact 66, the mechanism will be under automatic control, as for normal operation. Switch 60 is of such type that contact 71 will remain engaged in closed position until it is manually released for snap movement to the "off" position indicated in Figure 1. When moving contact 71 engages contact 66 current will flow through coil 51 by the following holding coil actuating circuit: from power line 46 through lead 61, movable contact 71, lead 65, float controlled switch 62, and leads 63 and 58 to coil 51 to energize the latter and move the contact supporting element 50 to cause current to be supplied motor 10. However, it will be obvious that coil 51 cannot be energized unless the water level is low in carbonator 17 and, for that reason, motor 10 will not be operated except under such condition.

Assuming that the water supply is low to cause the mercury switch 62 to close and thereby energize holding coil 51 to operate motor 10, the coil 31 which controls refrigerant suction valve 29 will also be energized because it is in parallel with holding coil 51, through switch 62a. Valve 29 will thereby be moved to its fully opened position to enable the refrigerant in unit 15 to evaporate at lower pressure and thereby cool the water supplied by pump 11 to the lowest desired temperature.

The above opening of valve 29 will occur regardless of whether thermostatic switch 35 is open or closed because the latter is simply in parallel with the holding coil actuating circuit described above as well as in parallel with the circuit described above for energizing the coil 31. However, if thermostatic switch 35 is open because the temperature of the water standing in coil 14 is low, it will close immediately water moves into the coil from pump 11.

Motor 10 will operate until the water level in carbonator 17 rises to a predetermined point, when mercury switch 62 will be opened to cause holding coil 51 to be deenergized and thereby stop motor 10. Switch 62a will simultaneously open, but since switch 60 is still closed through contact 71, current will flow to the suction valve opening coil 31 through the parallel and alternatively effective circuit including lead 65, thermostatically operated switch 35, lead 66, lead 58a, and, on the opposite side of the coil, through lead 55 to power line 43. As a result, valve 29 will be held in its fully opened position until the water temperature drops sufficiently to cause thermostatically operated switch 35 to be opened. When this occurs, coil 31 will be deenergized so that suction valve 29 may move to a more nearly closed position, thereby maintaining a higher pressure in the unit 15 and preventing the non-flowing water from being cooled to the same extent as when valve 29 is wide open.

When the water level of the carbonator 17 again drops, holding coil 51 will be again energized to start the motor 10 and suction valve coil 31 will also be immediately energized to fully open valve 29 so that the incoming water will be promptly cooled. The thermostatic switch 35 will then be closed for a new cycle of its operation because the incoming water will sufficiently raise the temperature of the heretofore standing water in coil 14 to cause such closing.

It will be noted that by the Figure 1 circuit, there is no lag in placing the unit 15 under the desired low pressure when the flow of water starts. There is a lag in increasing the pressure in the unit 15 when the flow of water stops but this is

of no consequence in operation with a carbonator because the lag only results in the water becoming somewhat cooler and thereby balances the slight lag in cooling which might be encountered in some installations because of the initial entry of warmer water when the motor starts. In addition, in carbonating water, there is no objection to having the water slightly cooler than the desired setting, though there is a substantial objection to having the water somewhat warmer than desired.

Referring to Figure 2, the structure disclosed therein is identical with that disclosed in Figure 1 except that only one float 18 and a float operated switch 62 are used. The circuit is also identical with that of Figure 1, except that by the Figure 2 arrangement, the leads 64a and 66a and switch 62a are omitted so that the holding coil 31 and a float operated switch (such as 62a of Figure 1) are not in parallel with switch holding coil 51. The Figure 2 arrangement causes holding coil 31 of valve 29 to be controlled to some extent by the temperature of the water. However, as hereinafter explained, the water temperature depends to a large extent upon whether pump 11 is supplying water to coil 14.

The operation of the Figure 2 circuit is as follows: When the movable contact 70 of switch 60 is moved to closed position by an operator, as would be the case for testing, the circuit would be from common return line 46 through lead 61, moving contact 70, contact 59, leads 58, switch holding coil 51, and lead 52 to power line 43 causing the contact supporting element 50 to operate so that the current will be supplied to pump motor 10, regardless of whether the water in the carbonator is sufficiently low to cause mercury switch 62 to be closed. However, if the water level in carbonator 17 is not at its upper limit, and if the thermostatically controlled switch 35 is closed by reasons of the fact that the water is not too cold, valve opening coil 31 will be energized to open valve 29 to the widest possible position so that a low pressure will be maintained in unit 15. It will be understood that switch 60 will be of such type that contact 70 will move to open position from that just described as soon as the operator removes his hand therefrom and, thereby, the circuits described will all open.

By the automatic and normally used circuit of Figure 2, which is set up when an operator moves movable contact 71 against fixed contact 66, in which position it will remain until manually returned to the open position shown, the circuit will be as follows: From power line 46 and lead 61 to movable contact 71 and thence through contact 66, lead 65 and float operated switch 62 to switch operating coil 51 if the water in the carbonator is low. Assuming that the water is low, switch operating coil 51 will be energized to cause current to flow to pump motor 10 so that water will flow through unit 15. Thermostatically operated switch 35 will close when warm water enters the coil 14 and current will then flow to valve opening coil 31 to open the valve 29 so that a low pressure will be maintained in unit 15 and the water will be cooled to the desired low temperature. It will be observed that while valve opening coil 31 is directly responsive to thermostatically operated switch 35, the operation of the latter is sensitive to operation of the pump.

When the water level rises to thereby open switch 62, switch operating coil 51 will open to stop the motor 10 but valve opening coil 31 will remain

energized through the parallel and alternatively effective circuit through leads 65, 66, 58a and 55 until the temperature of the water in coil 14 drops to too great an extent and thermostat 35 hereby opens. When this occurs, coil 31 will be deenergized and a higher pressure will be maintained in unit 15. When the switch 62 again closes, switch operating coil 51 will again be energized to start motor 10 and if the water temperature is high enough, coil 31 will be energized. When motor 10 starts, water entering coil 14 will, of course, cause switch 35 to close if it is open.

It will be clear that the pressure and temperature ranges used with the Figure 2 arrangement can be similar to those stated in connection with Figure 1.

In some installations, the Figure 2 arrangement will not be as desirable as that of Figure 1 because, with the Figure 2 system, there may be a lag in placing unit 15 under low pressure due to the fact that energization of coil 31 is, to a certain extent, responsive to the water temperature. However, the temperature of the water in coil 14 depends upon whether pump 11 is operating and if the pump stops, as occurs when the float rises to open switch 62, the water temperature will drop. Also, when the pump starts, as when the float drops, the water temperature will immediately rise. Hence, even in the Figure 2 arrangement, the coil 31 is responsive to whether the pump and its motor 10 are actuated.

Figure 3 discloses another control circuit wherein the pressure in unit 15 is more directly and immediately responsive to operation of pump motor 10 than the Figure 1 arrangement. By the Figure 3 system, the float controlled mercury switch 62 is connected to the contact 66 by a lead 75 and to switch holding coil 51 by a lead 76. Lead 76 is connected to contact 59 by a lead 77. The movable contacts of switch 60 are connected by a lead 78 to common return line 80 of a three wire system also including lines 81 and 82. Coil 51 operates to close motor leads 83, 84, and 85 and leads 86 and 87 connected to motor leads 83 and 85 place valve operating coil 31 in parallel with the water pump motor 10. By this arrangement, when the float controlled switch 62 causes motor 10 to be placed in operation, valve opening coil 31 will immediately be energized to move valve 29 to its fully opened position so that maximum cooling can be exerted upon the water moving through unit 15. When the water level rises to open switch 62, the motor will stop and flow of water will be discontinued but valve opening coil 31 will instantly be deenergized so that valve 29 may be moved by its spring or other means to a more fully closed position, thereby placing unit 15 under higher pressure and preventing the water from having too low a temperature.

It will be observed that by the Figure 3 arrangement, there is no lag whatever in operation of valve opening coil 31 and the evaporating point of the refrigerant is directly responsive to whether water is flowing. Since a greater amount of heat must be removed from flowing water than from non-flowing water to bring the two to the same temperature, it will be clear that even though a lower pressure is maintained in unit 15 while the water is flowing, the non-flowing water can be maintained at the identical temperature by raising unit 15 to a somewhat higher pressure. For example, a pressure of 32 lbs. can be maintained in unit 15 while the water is running to cool the water to 36°. When

motor 10 stops, valve 29 may close sufficiently to maintain a pressure of 36 lbs. in the unit with the result that the standing water will thereby likewise be maintained at 36°. Hence, by the Figure 3 arrangement, the temperature of the water can be held constant regardless of whether it is flowing or non-flowing. Therefore, if it is desired to do so, the temperature of the water can always be maintained only very slightly above freezing without danger of freezing ever occurring.

In the Figure 3 arrangement if movable contact 10 is held in engagement with contact 69, the water pump motor circuit will close and valve 29 will be held open, all entirely independent of the position of float 62.

In the use of any of the automatic contact arrangements described above, if the pressure maintained in unit 15 when suction valve 29 is wide open is such as to cool flowing water to 36°, for example, the higher pressure maintained when valve 29 is more nearly closed will still be low enough to cool the standing water to 36°. It will be obvious that while water is flowing, the pressure of the refrigerant in unit 15 may be so very low that a substantial volume of water can be cooled to a point close to freezing, but that when flow stops, a pressure sufficient to prevent freezing can be maintained. Thus, advantage can safely be taken of the full efficiency of a heat exchange unit, and the period of operation of the water pump or other supply means also can be reduced.

If a thermostatically controlled switch such as 35 in Figures 1 and 2 is used, such switch can be set to open when the temperature drops to about 33°.

In the example disclosed, the invention is shown used with a heat exchange unit of the water cooling type, the unit, furthermore, being of the flooded type. As has been stated above, other heat exchange elements can be controlled by the invention and, if cooling is to be performed, the cooling unit need not be of the flooded type.

The terminology used in the specification is for the purpose of description and not of limitation, the scope of the invention being defined in the claims.

This application is a continuation-in-part of my application Serial No. 411,599, filed September 19, 1941.

I claim:

1. In a heat exchange system for use with a heat exchange medium readily vaporizable at ordinary temperatures, a heat exchange element to bring a liquid to be treated and the medium into heat exchanging relation, means for delivering the liquid to be treated to said element, an actuating circuit for said liquid delivering means, and means in said actuating circuit to maintain the heat exchange medium within said heat exchange element at a plurality of definite pressures.

2. In a heat exchange system for use with a heat exchange medium readily vaporizable at ordinary temperatures, a heat exchange element to bring a liquid to be treated and the medium into heat exchanging relation, means for delivering the liquid to be treated to said element, an actuating circuit for said liquid delivering means, a second circuit in parallel with the first circuit, and means in the second circuit to maintain the medium within said heat exchange element at a plurality of definite pressures.

3. In a heat exchange system for use with a heat exchange medium readily vaporizable at ordinary temperatures, a heat exchange element to bring a liquid to be treated and the medium into heat exchanging relation, means for delivering the liquid to be treated to said element, means to receive the treated liquid from said element, an actuating circuit for said liquid delivering means, means in said circuit responsive to the quantity of liquid in said liquid receiving means, and means controlled by said circuit to maintain the heat exchange medium at a plurality of definite pressures. 5
4. In a heat exchange system for use with a heat exchange medium readily vaporizable at ordinary temperatures, a heat exchange element to bring a liquid to be treated and the medium into heat exchanging relation, means for delivering the liquid to be treated to said element, means to receive the liquid from said heat exchange element, an actuating circuit for said liquid delivering means, means in said circuit responsive to the quantity of liquid in said liquid receiving means and the temperature of the liquid treated by said heat exchange element, and means controlled by said circuit to maintain the heat exchange medium at a plurality of definite pressures. 10
5. In a heat exchange system for use with a heat exchange medium readily vaporizable at ordinary temperatures, a heat exchange element to bring a liquid to be treated and the medium into heat exchanging relation, means for delivering the liquid to be treated to said element, an actuating circuit for said liquid delivery means, and means solely responsive to flow of current in said circuit to maintain the medium within said heat exchange element at a plurality of definite pressures. 15
6. In a heat exchange system for use with a heat exchange medium readily vaporizable at ordinary temperatures, a heat exchange element to bring a liquid to be treated and the medium into heat exchanging relation, means for delivering the liquid to be treated to said element, means to receive the treated liquid from said element, an actuating circuit for said liquid delivering means, said circuit having means associated therewith responsive to the temperature of the treated liquid, means to maintain the heat exchange medium within said heat exchange element at a plurality of definite pressures, said last-named means being so connected in said circuit as to be partially responsive to actuation of said liquid delivering means and partially responsive to said temperature controlled means. 20
7. In a heat exchange system for use with a heat exchange medium readily vaporizable at ordinary temperatures, a heat exchange element to bring a liquid to be treated and the medium into heat exchanging relation, means for delivering the liquid to be treated to said element, means to maintain the heat exchanging characteristics of the heat exchange medium at definite factors, a pair of alternatively effective circuits for controlling said last-named means, one of said circuits being responsive to operation of said liquid delivering means, and the other of said circuits being responsive to the temperature of the treated liquid. 25
8. In a heat exchange system for use with a heat exchange medium readily vaporizable at ordinary temperatures, a heat exchange element to bring a liquid to be treated and the medium into heat exchanging relation, means for delivering the liquid to be treated to said element, means to receive the treated liquid from said element, means to maintain the heat exchanging characteristics of the heat exchange medium at definite factors, a pair of alternatively effective circuits for controlling said last-named means, one of said circuits being responsive to the level of liquid in said liquid receiving means, and the other of said circuits being responsive to the temperature of the treated liquid. 30
9. In a heat exchange system for use with a heat exchange medium, a heat exchange element to bring the medium and a liquid to be treated in heat exchanging relation, means to deliver a liquid to be treated to said element, means to receive treated liquid from the element, means responsive to the level of liquid in said treated liquid receiving means to control operation of said liquid delivery means, and means including thermostatic means directly responsive to the temperature of the treated liquid to control the pressure of the heat exchange medium. 35
10. In a heat exchange system for use with a heat exchange medium readily vaporizable at ordinary temperatures, a heat exchange element to bring a liquid to be treated and the medium into heat exchanging relation, means for delivering the liquid to be treated to said element, means to receive the treated liquid from said element, an actuating circuit for said liquid delivering means, means controlled by said circuit to maintain the heat exchange medium within said heat exchange element at a plurality of definite pressures, said circuit having means associated therewith responsive to the quantity of liquid in said liquid receiving means, additional means associated with said circuit responsive to the temperature of the treated liquid, said two last-named means being so connected that the actuating circuit will be closed when the liquid in said liquid receiving means reaches a predetermined level and will open when the temperature of the treated liquid reaches a predetermined point. 40
11. In a heat exchange system for use with a heat exchange medium readily vaporizable at ordinary temperatures, a heat exchange element to bring a liquid to be treated and the medium into heat exchanging relation, means for delivering the liquid to be treated to said element, means to receive the treated liquid from said element, an actuating circuit for said liquid delivering means comprising a float operated switch adapted to close when the liquid in said receiving means drops to a predetermined level, means in parallel with said circuit including a second float operated switch in said receiving means to maintain the heat exchange medium within said heat exchange element at a predetermined pressure, and a second circuit to maintain the exchange medium at said predetermined pressure comprising a thermostatic switch responsive to the temperature of the liquid. 45
12. In a heat exchange system for use with a heat exchange medium readily vaporizable at ordinary temperatures, a heat exchange element to bring a liquid to be treated and the medium into heat exchanging relation, means for delivering the liquid to be treated to said element, an actuating circuit for said liquid delivering means, a valve to control flow of the medium with respect to said heat exchange element, and means in said actuating circuit in parallel with said liquid delivering means to control operation of said valve. 50
13. In a heat exchange system for use with a heat exchange medium readily vaporizable at ordinary temperatures, a heat exchange element 55

to bring a liquid to be treated and the medium into heat exchanging relation, means for delivering the liquid to be treated to said element, an actuating circuit for said liquid delivering means, a valve to control flow of the medium with respect to said heat exchange element and adapted to lower the pressure of the medium in said element when in opened position, and means controlled by said actuating circuit to open said valve when said liquid delivering means is operating.

14. In a heat exchange system for use with a heat exchange medium readily vaporizable at ordinary temperatures, a heat exchange element to bring a liquid to be treated and the medium into heat exchanging relation, means for delivering the liquid to be treated to said element, means to maintain the pressure of said medium in said element at predetermined points, and means to operate said last-named means to maintain the pressure of the medium at a low pressure when said means for delivering the liquid to said element is operating.

15. In a heat exchange system for use with a heat exchange medium readily vaporizable at ordinary temperatures, a heat exchange element to bring a liquid to be treated and the medium into heat exchanging relation, means for delivering

the liquid to be treated to said element, an actuating circuit for said liquid delivering means, means in said actuating circuit to maintain the heat exchange medium within said heat exchange element at a plurality of definite pressures, a compressor for said medium, and an operating circuit for said compressor including controls independent of said actuating circuit for said liquid delivering means.

16. In a heat exchange system for use with a heat exchange medium readily vaporizable at ordinary temperatures, a heat exchange element to bring a liquid to be treated and the medium into heat exchanging relation, means for delivering the liquid to be treated to said element, means to receive the treated liquid from said element, an actuating circuit for said liquid delivering means comprising a float operated switch adapted to close when the liquid in said receiving means drops to a predetermined level, a thermostatic switch responsive to the temperature of the liquid in said element, and means directly responsive to said thermostatic switch to maintain the heat exchange medium within said heat exchange element at a predetermined pressure.

25

ROBERT J. STEWART.
